POSITIVE ACTING CIRCULAR CHASER DIE

Alfred E. Drissner, Cleveland, Ohio, assignor to
 The National Acme Company, Cleveland, Ohio,
 a corporation of Ohio

Application May 22, 1937, Serial No. 144,228

20 Claims.

(Cl. 10—96)

This invention relates to threading dies for use on automatic screw machines, the object of the invention being to provide an improved positive acting die in which the cutters or chasers are positively expanded or retracted in an efficient manner and which die is simple in construction and operation.

In the drawings accompanying and forming a part of this specification, Fig. 1 is a side view of this improved die.

Fig. 2 is a front end view thereof.

Fig. 3 is a longitudinal sectional view.

Fig. 4 is a section on line 4—4 of Fig. 3, looking in the direction of the arrows.

Fig. 5 is a perspective view of the cam holder with the cams removed.

Fig. 6 is a perspective view of one of the cams for use in the cam holder of Fig. 5.

Fig. 7 is a sectional view on line 7—7 of Fig. 1, looking in the direction of the arrows.

Fig. 8 is a longitudinal section on line 8—8 of Fig. 7, looking in the direction of the arrows.

Fig. 9 is a detail perspective view of the several parts of the die disassembled, and

Fig. 10 is a perspective view of a chaser block showing in dotted lines a circular chaser applied thereto.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawings since the invention is capable of other embodiments, and that the phraseology employed is for the purpose of description and not of limitation.

In the preferred form, this improved die comprises a die body 2 having an enlarged head 3 having radially extending slots 4 of T-shape therein for the reception of similarly formed chaser blocks 5 adapted to carry chasers 6 which are shown herein as of circular form. The die body has an extended bored shank 7 for attachment to suitable holding means of a screw machine, whereby the die is rotated.

Slidably carried on the body 2 is a hood 8 having an annular recess 9 in the periphery thereof for the reception of a yoke, not shown, carried by the machine whereby the hood is shifted back and forth. Within this hood 8 is an inwardly projecting annular cam 10 in position to cooperate with a pair of oppositely located segmentally formed shiftable cams 11 (see Fig. 4)

having inclined cam faces 12 (see Fig. 6). These cams 11 are carried in opposed segmental recesses of an annular cam holder or carrier 13 located on the inner end of the shank 7 and within the hood 8. These cams are in position to be operated by the cam 10 as the hood is shifted back and forth and are held in projected position by suitable springs 14 (see Fig. 4) located in opposed faces of the cams and cam holder and in their projected position they engage the rear face of an annular sliding ring 15 carried on the cam holder 13 and in juxtaposition to the rear face of the head 3. This ring 15, upon the depression of the cams 11, will be shifted rearwardly on the cam holder 13 by suitable springs 16 located in opposed faces of the ring 15 and die head 3.

This sliding ring 15 carries a series of longitudinally extending cam studs 16 secured to the ring by pins 16' and adapted to project through suitable openings 17 in the head 3 and provided with tapered cams or keys 18 (see Fig. 9). Each of these keys 18 engages a similarly formed cam slot 19 in a chaser block 5 adapted to slide in the radial slot 4 of the head 3.

Threaded on the shank 7 is a collar 24 in position to engage the rear face of the cam holder 13 and hold the parts properly assembled and also effective to adjust the position of the cam holder 13. Adjustment of this collar 24 in either direction effects a like movement of this cam holder 13, cams 11, ring 15, studs 16 and thereby, through the cams or keys 18, shifts the chaser blocks and their chasers inwardly or outwardly radially. By adjustment of this collar toward the chasers, the chasers are adjusted to cut a smaller diameter of work. Suitable springs 13' co-operate with the cam holder 13 and rear face of the die body for holding the cam holder in engagement with the collar 24.

A retaining block 25 having an elongated slot 26 is suitably secured on this collar 24 by means of a screw and limits the backward movement of the ring 15 and its associated parts and prevents the keys 18 from riding beyond the slots 19 in the chaser blocks 5 and thus also prevents the blocks from falling out of the die. This retaining block 25 may be moved backward to permit the cams 18 to disengage the slots 19 of the blocks 5 when it is desired to remove the blocks for the insertion of new or reground chasers.

Suitably removably secured within the body 2 as by a bayonet joint 27 and projecting between the chasers is a work guide member 28 having projecting tines 29 extending between the chasers, 55

to prevent the work falling between the chasers when the die is in open position.

To insure the positive action of this die, elongated slots 21 (see Fig. 3) are provided in the hood 8 and through these slots suitable screws 22 project into the ring 15. When the hood 8 contacts these screws 22, the expanding action of the chasers is started if for any reason the springs 20 fail to do this work. After the expanding action of the chasers is started, the springs will complete the expanding action as before described.

The operation of the die is as follows:

Just before the completion of the threading operation, the yoke carried by the machine and engaging the hood 8 in the annular recess 9 holds back the hood as the other parts of the die continue their forward travel. The annular cam 10 on the inside of the hood rides up the inclined surface 12 of the cams 11 thereby depressing them within the cam holder 13 against the action of the springs 14. As these cams are pressed within the periphery of the holder 13, the locking action of the cams against the rear face of the ring 15 is released and the springs 20 acting against the die head 3 force the ring 15 to the ear and with it the cam rods 16 and due to the sliding action of the keys 18 in slots 19 of the blocks 5, the chasers are released from the work.

To reset the die, the spindle is moved backward until the yoke engaging in the groove 9 of the hood 8 is stopped. The body of the die continues to move back until the flanged face 23 of the hood contacts the rear face of the ring 15 thus holding this ring stationary and permitting the cams 11 to expand or project outward by means of the springs 14, thus locking the ring 15 in place.

It is to be understood that, by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A threading die comprising a body, a plurality of radially shiftable chasers and a carrier carried thereby, positive acting means for shifting the chasers and comprising a sliding member, means for locking said member, both of said means carried by the carrier, and a shiftable hood for controlling the operation of and directly engaging said locking means and effective to release the locking means by depression thereof.

2. A threading die comprising a body, a plurality of radially shiftable chasers and a cam carrier carried thereby, positive acting means for shifting the chasers and comprising a sliding member, means for locking said member and comprising a shiftable cam, both of said means carried by the cam carrier, and a shiftable hood for controlling the operation of and directly engaging said locking means and effective to release the locking means by depression thereof.

3. A threading die comprising a body, a plurality of radially shiftable chasers and a carrier carried thereby, positive acting means for shifting the chasers and comprising a sliding member, means for locking said member, both of said means carried by the carrier, a shiftable hood for controlling the operation of and directly engaging said locking means and effective to release the

locking means by depression thereof, and means for adjusting the position of the locking means and thereby the diameter of the chasers.

4. A threading die comprising a body, a plurality of radially shiftable chasers and a cam carrier carried thereby, positive acting means for shifting the chasers and comprising a sliding member, means for locking said member and comprising a shiftable cam, both of said means carried by the cam carrier, a shiftable hood for controlling the operation of and directly engaging said locking means and effective to release the locking means by depression thereof, and means for adjusting the position of the locking means and thereby the diameter of the chasers.

5. A threading die comprising a body, a plurality of radially shiftable chasers and a cam carrier carried thereby, positive acting means for shifting the chasers and comprising a sliding ring, said cam carrier projecting into said ring and provided with shiftable cams for locking the ring, and a hood having a cam directly engaging said shiftable cams for controlling said cams whereby on the depression thereof said ring will be released to permit sliding thereof.

6. A threading die comprising a body, a plurality of radially shiftable chasers and a cam carrier carried thereby, positive acting means for shifting the chasers and comprising a sliding ring, said cam carrier projecting into said ring and provided with shiftable cams for locking the ring, a hood having a cam directly engaging said shiftable cams for controlling said cams whereby on the depression thereof said ring will be released to permit sliding thereof, and means for adjusting said cam carrier for controlling the diameter of the chasers.

7. A threading die comprising a body, a plurality of radially shiftable chaser carrying blocks carried thereby and having inclined slots, a cam carrier encircling said body, positive acting means for shifting the blocks and comprising a sliding ring having forwardly projecting cam formed studs co-operating with the slots of the chaser blocks, said cam carrier projecting into said ring and provided with radially shiftable cams for locking the ring, and a shiftable hood having a cam directly engaging said shiftable cams for controlling the operation of said cams whereby on the depression thereof said ring will be released to permit sliding thereof.

8. A threading die comprising a body, a plurality of radially shiftable chaser carrying blocks carried thereby and having inclined slots, a cam carrier encircling said body, positive acting means for shifting the blocks and comprising a sliding ring having forwardly projecting cam formed studs co-operating with the slots of the chaser blocks, said cam carrier projecting into said ring and provided with radially shiftable cams for locking the ring, a shiftable hood having a cam directly engaging said shiftable cams for controlling the operation of said cams whereby on the depression thereof said ring will be released to permit sliding thereof, and means for adjusting the cam carrier thereby to adjust the diameter of the chasers carried by the blocks.

9. A threading die comprising a body, a plurality of radially shiftable chaser carrying blocks carried thereby and having inclined slots, a cam carrier encircling said body, positive acting means for shifting the blocks and comprising a sliding ring having forwardly projecting cam formed studs co-operating with the slots of the chaser blocks, resilient means co-operating with the body

and ring for shifting the ring rearwardly, said cam carrier projecting into said ring and provided with radially shiftable spring actuated cams for locking the ring, and a shiftable hood having a cam directly engaging said shiftable cams for controlling the operation of said cams whereby on the depression thereof said ring will be released to permit sliding thereof.

10. A threading die comprising a body, a plurality of radially shiftable chaser carrying blocks carried thereby and having inclined slots, a cam carrier encircling said body, positive acting means for shifting the blocks and comprising a sliding ring having forwardly projecting cam formed studs co-operating with the slots of the chaser blocks, said cam carrier projecting into said ring and provided with radially shiftable cams for locking the ring, a shiftable hood having a cam directly engaging said shiftable cams for controlling the operation of said cams whereby on the depression thereof said ring will be released to permit sliding thereof, and means co-operating with the ring and the hood for shifting the ring in one direction on the movement of the hood.

25. 11. A threading die comprising a body, a plurality of radially shiftable chaser carrying blocks carried thereby and having inclined slots, a cam carrier encircling said body, positive acting means for shifting the blocks and comprising a sliding ring having forwardly projecting cam formed studs co-operating with the slots of the chaser blocks, said cam carrier projecting into said ring and provided with radially shiftable cams for locking the ring, a shiftable hood having a cam directly engaging said shiftable cams for controlling the operation of said cams, resilient means co-operating with the body and the ring for shifting the ring upon depression of said cams, and means co-operating with the ring and hood for insuring the shifting movement of the ring in one direction.

12. A threading die comprising a body, a plurality of radially shiftable chaser carrying blocks carried thereby and having inclined slots, positive acting means for shifting the blocks and comprising a sliding ring having forwardly projecting cam formed studs co-operating with the slots of the chaser blocks, resilient means co-operating with the body and ring for shifting the ring, an annular cam carrier carried by the body and projecting into said ring and provided with radially shiftable spring actuated cams for locking the ring, a shiftable hood having a cam directly engaging said shiftable cams for controlling the operation of said cams, whereby on the depression of said spring actuated cams said sliding ring will be released, means co-operating with the ring and hood for insuring the shifting of the ring in one direction on the movement of the hood, and an adjustable collar co-operating with the cam carrier for adjusting the position of the chaser blocks and thereby the chasers.

13. A threading die comprising a body having a shank, a plurality of radially shiftable chaser carrying blocks carried by the body and having inclined slots, positive acting means for shifting the blocks and comprising a sliding ring having forwardly projecting cam formed studs projecting through the body and co-operating with the slots of the chaser blocks, an annular cam carrier carried by the shank and projecting into the ring and provided with radially shiftable cams for locking the ring, and a shiftable hood having an inwardly extending cam directly engaging said shiftable cams for controlling the operation of

said shiftable cams whereby on the depression thereof said ring will be released thereby to permit sliding of said ring.

14. A threading die comprising a body having a shank, a plurality of radially shiftable chaser carrying blocks carried by the body and having inclined slots, positive acting means for shifting the blocks and comprising a sliding ring having forwardly projecting cam formed studs projecting through the body and co-operating with the slots of the chaser blocks, an annular cam carrier carried by the shank and projecting into the ring and provided with radially shiftable cams for locking the ring, a shiftable hood having an inwardly extending cam directly engaging said shiftable cams for controlling the operation of said shiftable cams whereby on the depression thereof said ring will be released thereby to permit sliding of said ring, and an adjustable collar carried by the shank and in engagement with the cam carrier for adjusting the position thereof and thereby the diameter of the chasers.

15. A threading die comprising a body, a plurality of radially shiftable chasers and a carrier carried thereby, positive acting means for shifting the chasers and comprising a sliding member, means for locking said member, both of said means carried by the carrier, a shiftable hood for controlling the operation of and directly engaging said locking means and effective to release the locking means by depression thereof, and work guiding means carried by the body and projecting between the chasers, to prevent the work falling between the chasers when the die is open.

25. 16. A threading die comprising a body, a plurality of radially shiftable chasers and a carrier carried thereby, positive acting means for shifting the chasers and comprising a sliding member, means for locking said member, both of said means carried by the carrier, and a shiftable hood for controlling the operation of and directly engaging said locking means and effective to release the locking means by depression thereof, and a detachable work guiding means carried by the body.

30. 17. A threading die comprising a body, a plurality of radially shiftable chaser carrying blocks carried thereby and having inclined slots, positive acting means for shifting the blocks and comprising a sliding ring having forwardly projecting cam formed studs co-operating with the slots of the chaser blocks, a cam carrier encircling the body and projecting into said ring and provided with radially shiftable cams for locking the ring, a shiftable hood having a cam directly engaging said shiftable cams for controlling the operation of said cams whereby on the depression thereof said ring will be released thereby to permit sliding of said ring, and a detachable work guiding means carried by the body.

35. 18. A threading die comprising a body having a shank, a plurality of radially shiftable chaser carrying blocks carried by the body and having inclined slots, positive acting means for shifting the blocks and comprising a sliding ring having forwardly projecting cam formed studs projecting through the body and co-operating with the slots of the chaser blocks, an annular cam carrier carried by the shank and projecting into the ring and provided with radially shiftable cams for locking the ring, a shiftable hood having an inwardly extending cam directly engaging said shiftable cams for controlling the operation of said shiftable cams whereby on the

depression thereof said ring will be released thereby to permit sliding of said ring, and a detachable work guiding means carried by the body.

19. A threading die comprising a body, a plurality of radially shiftable chaser carrying blocks carried by the body and having wing extensions adapted to engage the face of the body, a carrier encircling said body, positive acting means for shifting the chasers and comprising a sliding member, means for locking said member, both of said means carried by the carrier, and a shiftable hood for controlling the operation of and directly engaging said locking means and effective to release the locking means by depressions thereof.

20. A threading die comprising a body having a shank, a plurality of radially shiftable chaser carrying blocks carried by the body and having wing extensions adapted to engage the front face of the body and also having inclined slots,

positive acting means for shifting the blocks and comprising a sliding ring having forwardly projecting cam formed studs co-operating with the slots of the chaser blocks, resilient means co-operating with the body and ring for shifting the ring rearwardly, an annular cam carrier mounted on the shank and projecting into said ring and provided with radially shiftable spring actuated cams for locking the ring, springs co-operating with the body and cam carrier, a shiftable hood having a cam directly engaging said shiftable cams and effective to depress the cams of the cam carrier and thereby release the stud carrying ring thereby to shift the chasers, and an adjustable collar carried by the shank and co-operating with the cam carrier to adjust the position thereof and thereby adjust the position of the chasers.

ALFRED E. DRISSNER. 20.
